US00D903406S

(12) **United States Design Patent** (10) Patent No.: **US D903,406 S**
 McCabe et al. (45) Date of Patent: ** Dec. 1, 2020

(54) **BEVERAGE CONTAINER LID**(71) Applicant: **Leapfrog Product Development LLC**, Chicago, IL (US)(72) Inventors: **Micaela K. McCabe**, Chicago, IL (US); **Brian M. Clemens**, Burnsville, MN (US); **Steven N. Pinelli**, Ogden Dunes, IN (US); **Glen C. Gilmore, III**, Naperville, IL (US); **Richard E. Ellison**, Chicago, IL (US); **Derek J. Leatzow**, Chicago, IL (US); **Kurtis M. Sward**, Anna Maria, FL (US)(73) Assignee: **Leapfrog Product Development LLC**, Chicago, IL (US)(**) Term: **15 Years**(21) Appl. No.: **29/684,573**(22) Filed: **Mar. 22, 2019**(51) LOC (12) Cl. **07-99**

(52) U.S. Cl.

(57) **CLAIM**

We claim the ornamental design for a beverage container lid, as shown and described.

DESCRIPTION

FIG. 1 is a top perspective view of the beverage container lid according to the new design.

FIG. 2 is a bottom perspective view of the beverage container lid shown in FIG. 1.

FIG. 3 is a front elevation view of the beverage container lid shown in FIG. 1.

FIG. 4 is a rear elevation view of the beverage container lid shown in FIG. 1.

FIG. 5 is a left side elevation view of the beverage container lid shown in FIG. 1.

FIG. 6 is a right side elevation view of the beverage container lid shown in FIG. 1.

FIG. 7 is a top plan view of the beverage container lid shown in FIG. 1; and,

FIG. 8 is a bottom plan view of the beverage container lid shown in FIG. 1.

The broken lines illustrating a beverage container depict environment and form no part of the claimed design. All other broken lines depict portions of the beverage container lid that form no part of the claimed design.

1 Claim, 8 Drawing Sheets

FIG. 1

FIG. 2

FIG. 3

FIG. 4

FIG. 5

FIG. 6

FIG. 7

FIG. 8
